ORNAMENTAL LIGHTING FIXTURE

Louis P. Tuttle, Glendale, Calif.

Application August 4, 1947, Serial No. 765,872

1 Claim. (Cl. 240—10)

1

This invention relates to ornamental lighting fixtures and in particular to Christmas tree lights.

One object of the invention is to provide ornamental lights for Christmas trees. Another object is to provide an ornamental electric light fixture which may be removably connected to a pair of conductors at any position thereon. A further object is to provide means for making removable electrical connection to a lighting fixture.

These and other objects are attained by my invention which will be understood from the following description, reference being made to the accompanying drawings in which:

Fig. 1 is a side elevational view partly in section showing a preferred form of my invention;

Fig. 2 is a fragmentary cross-sectional view showing the means for making electrical connection;

Fig. 3 is a cross-sectional view taken on the line 3—3 of Fig. 1; and

Fig. 4 is a fragmentary cross-sectional view showing a typical removable light-transmitting ornamental figure for use with my fixture.

Referring to the drawings, my light fixture consists of a body 11 having an electrical lamp socket 12 mounted thereon and preferably embedded therein, the threaded terminal 13 and the central button terminal of the socket being electrically connected by the conductors 15 and 16, each of which is provided at its other end with a sharp-pointed electric contact member 17. The members 17 may be single-pointed, but are preferably three-pointed as shown to insure electrical contact. The contact members 17 are preferably embedded in the walls 18 of a cylindrical cavity 19 arranged coaxially with the socket 12 on the underside of the body 11. The conductors 15 and 16, preferably wires, are embedded in the body 11, which is conveniently made of plastic insulating material, for example, polystyrene. Openings 20 on opposite sides of the wall 18 are provided for the entrance and exit of a pair of side-by-side insulated electric conductors 21, the sharp contact members 17 being disposed on opposite sides intermediate the openings 20 with the points 17 adjacent the conductors and positioned to penetrate the insulation 22 to make electric contact with the embedded metallic core 23. The core may be single or multiple strand wire.

A cavity 19 is provided with a closure member 24 having a cam piece 25 extending into the cavity 19 between the electric conductors 21, said cam 25 being shaped so that upon turning, it

2

presses both conductors 21 into contact with the respective adjacent sharp points 17, to thereby make electrical contact with the metallic cores 23. The closure member 24 is provided with lips 26 which are adapted to engage a flange 27 extending outwardly from the walls 18 surrounding the cavity 19, gaps 28 being provided in the flange 27 to permit the entrance of the lips 26. Upon turning the closure member 24, the cam 25 presses the conductors 21 into contact with the sharp points 17 and at the same time locks the closure member on to the body 11 by frictional engagement between lips 26 and the outstanding flange 27.

The closure member 24 is also provided with a spring clamp 29 adapted to attach the fixture to an object to be ornamenteally lighted, for example a limb of a Christmas tree, L.

The body 11 is conveniently provided with a reflector surface 31 arranged coaxially with the socket 12. The socket may also be provided with an upwardly extending threaded boss 32 adapted to make threaded engagement with a collar 33 which surrounds and encloses the miniature lamp 34 in the socket 12. The collar 33 may be conveniently made of light-transmitting material such as clear or translucent plastic. The upper edge 35 of the collar 33 is provided with threads 36 adapted to make threaded engagement with an ornamental object such as for examples, the candle 37 (as shown in Fig. 1) or the reindeer (as shown in Fig. 4). The ornamental objects are preferably made of light-transmitting molded synthetic plastic materials upon which clear or sand-blasted surfaces may be provided to produce different lighting effects. Various ornamental objects may be substituted for the representative candles and reindeer, as shown in the drawings.

When the collar 33 is made of light-transparent material, a soft glow is reflected from the reflector surface 31 to the ornamental object and gives varied and pleasing ornamental lighting effects.

The advantages of my invention, particularly for Christmas tree lighting, will be apparent. By using a pair of flexible insulated electric wires to carry the electrical current, the ornamental fixtures may be attached at any position along the conductors by merely placing the conductors in the channel provided between the cam 25 and the walls 18 of the body and then turning the cam so that the closure member is secured to the body and at the same time the electrical connection is made between points 17 and the

metallic core 23 of the conductors. With the ordinary soft resilient insulation, the positions may be changed upon occasion without serious injury to the wire conductors and their insulation. The ornaments may be selected and arranged in a string of lights as desired to produce the desired ornamental effect upon the Christmas tree or other object being lighted. The fixtures are readily formed by molding from synthetic plastic materials and may be produced at low cost. The spring clamps permit the attachment of each fixture where desired.

I claim:

An ornamental lighting fixture comprising a body having an electric lamp socket mounted centrally thereon and a reflector surface surrounding said socket, said reflector being adapted to receive downwardly directed light from a light-transmitting ornament mounted above said socket, said body having on its upper side an outside threaded hollow boss coaxial with said socket adapted to support an inside threaded collar, and said body having on its lower side opposite said socket a cylindrical cavity within a cylindrical wall having an interrupted flange extending outwardly from said wall, with openings through said cylindrical wall adapted for the entrance and exit of a pair of side-by-side insulated electrical conductors, and sharp-pointed electrical contact members electrically connected to said socket terminals embedded in opposite positions in said wall with said points directed inwardly and adapted to penetrate the insulation to make elec-

trical contact with said conductors; a threaded collar attachable to said boss, the upper end of said collar being arranged for removably attaching a light-transmitting ornament; and a closure member for the cylindrical cavity in said holder, including a cam member extending into said cavity between the side-by-side conductors and adapted upon rotation to press each of said conductors into contact with one of said pointed members, and flange-engaging lips arranged to pass through the gaps in said flange and upon rotation of said closure adapted to frictionally engage said flange; and spring clamp means attached to said closure member for removably attaching the fixture to a Christmas tree or the like.
